(57) CLAIM

The ornamental design for a sports memorabilia holder, as shown and described.

DESCRIPTION

FIG. 1 is a top and front perspective view of a sports memorabilia holder showing my new design, the broken-line disclosure of a basketball being for illustrative purposes only and forming no part of the claimed design;
FIG. 2 is an additional top and front perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.
